(57) **CLAIM**

What is claimed is the ornamental design for a garment-attachable cape, as shown and described.

DESCRIPTION

FIG. 1 is a perspective view of a garment-attachable cape, illustrated in a worn configuration, showing the new design; FIG. 2 is a front elevational view thereof, illustrated in a flat configuration;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines showing a person in FIG. 1 are included for the purpose of illustrating the invention in use, and form no part of the claimed design.

The broken lines, shown throughout the views on the surface of the cape, represent stitching.
